UNITED STATES PATENT OFFICE.

LOUIS S. FLATAU, OF ST. LOUIS, MISSOURI.

SEAL.

1,137,391.

Specification of Letters Patent. Patented Apr. 27, 1915.

Application filed October 3, 1914. Serial No. 864,756.

To all whom it may concern:

Be it known that I, LOUIS S. FLATAU, a citizen of the United States of America, a resident of the city of St. Louis, State of 5 Missouri, have invented certain new and useful Improvements in Seals, of which the following is a full, clear, and exact description, reference being had to the accompanying drawings, forming a part of this specification.

10 My invention relates to a seal, particularly adapted to seal the fastening devices of car doors, but it may be used as a sealing device for locks and latches of various different kinds, or, if desired, the new seal may be utilized as a sealing device for containers that are not provided with locks.

The main object of the invention is to produce an extremely simple and inexpensive 20 seal having a shackle and a connecting member for uniting the ends of said shackle. The connecting member is preferably a thin, flexible strip of inexpensive sheet metal adapted to receive the shackle, and adapted 25 to be bent with the shackle so as to securely connect the end portions of the latter.

Figure I is a front elevation of a seal embodying the features of my invention. Fig. II is a view similar to Fig. I, illustrating a 30 seal provided with an identification section adapted to be removed from the sealing elements. Fig. III is an enlarged fragmentary perspective view showing one end of the sheet metal connecting member and the 35 shackle adapted to be secured to said connecting member. Fig. IV is a side elevation showing the connecting member crimped and folded with the shackle to firmly connect the ends of the shackle.

40 1 designates a shackle, and 2 designates a connecting member for uniting the end portions of the shackle. The shackle is preferably a wire and the connecting member is preferably a thin, flexible strip of sheet 45 metal having its longitudinal margins curled, as shown most clearly in Fig. III, to produce a pair of passageways 3 and 4 for the reception of the ends of the shackle. One end of the shackle is arranged within 50 the passageway 4 and it may be secured by crimping the connecting member with the shackle, as indicated at 5 in Fig. I.

In the practical use of my seal, the free 55 end portion of the shackle is passed through the article to be sealed and thereafter in-

serted into the passageway 3 at one of the margins of the connecting member 2. To secure the shackle in the passageway 3 the metal forming said passageway may be crimped with the shackle, as shown at 6 in 60 Fig. IV, or, if desired, the connecting member may be folded by hand to produce a crimp 7, Fig. IV. In crimping or folding the sheet metal connecting member with the shackle, the distorted or mutilated metal of 65 these flexible elements produces a very firm connection, well adapted to resist attempts to open the shackle without breaking the seal, and owing to the flexibility of the mutilated elements, attempts to straighten them 70 will usually be indicated by additional bends or crimps which more firmly unite the connecting member with the shackle.

In Fig. II I have shown a connecting member 2' provided with a seal section 8 75 and an identification section 9 adapted to be broken from the seal section 8. The connecting member 2' is preferably weakened by a transverse slot 10 formed between the seal section 8 and the identification section 80 9 so that the identification section 9 may be readily broken from the seal section at the transverse slot 10. Obviously, these sections may be separated from each other by a cutting device or they may be broken apart by 85 bending the connecting member 2' several times to fracture the metal adjacent to the end of slot 10. The shackle 1, shown in Fig. II, is adapted to be inserted into the seal section 8 and thereafter crimped with said 90 seal section, as previously pointed out, and the identification section 9, broken from the seal section, may be used as evidence of ownership of the sealed property. The thin, flexible connecting member is preferably 95 provided with an aperture 11 for the reception of a wire or string upon which a number of the sealing devices may be strung. This aperture or perforation 11 is formed at the end opposite to the shackle receiving 100 end of the connecting member, so that the wire shackles will extend downwardly and away from the string which serves as a carrier or holder for the sealing devices.

I claim:—

A seal comprising a connecting member and a wire shackle associated therewith, the said connecting member being a long narrow strip of sheet metal having its longitudinal margins curled to provide passageways for 110

the reception of said shackle, the curled sheet metal forming one of said passage-ways being primarily crimped with one end of the shackle so as to permanently secure 5 only one end of the shackle to said sheet metal, and the said long narrow strip of sheet metal being folded on itself to produce

a crimp 7 wherein the other end of the shackle is secured.

LOUIS S. FLATAU.

In the presence of—
E. K. CLARK,
A. J. McCauley.
